UNITED STATES PATENT OFFICE.

THOMAS W. KEEN, OF SWISSVALE, PENNSYLVANIA.

VALVE-OPERATING MECHANISM.

1,053,732.

Specification of Letters Patent. Patented Feb. 18, 1913.

Application filed April 6, 1912. Serial No. 688,957.

To all whom it may concern:

Be it known that I, THOMAS W. KEEN, a citizen of the United States, residing at Swissvale, in the county of Allegheny and State of Pennsylvania, have invented certain new and useful Improvements in Valve-Operating Mechanisms, of which the following is a specification.

My invention pertains to the construction and arrangement of engine valve operating mechanism, and, while not restricted to such use, relates more particularly to the mechanism used in actuating the inlet and exhaust outlet valves on the extremely large type of internal combustion engines employing blast furnace gases as fuel.

The invention is designed to provide an engine valve operating mechanism having improved means whereby the valves are positively actuated in opening and closing the inlet and the exhaust outlet ports of the engine, and by which the valves are positively held in closed position or position of the valves during the major portion of the reciprocating movements of the engine piston.

Another object of the invention is to provide a valve operating mechanism having novel means whereby the large, heavy valves are counterbalanced, by which accelerated movement of the valves due to the weight of the extremely heavy valves and movement against pressure of the gases in the engine cylinder are avoided and overcome and the stresses on the valve operating mechanism are greatly lessened and reduced.

A further object of my invention is to provide a valve operating mechanism having novel adjusting means whereby compensation for increase in the length of the valve stems caused by expansion when in use and variations caused by wear of the moving parts is effected, the presence of lost motion in the valve operating gear is avoided and prevented and proper timing of the valves in opening and closing is obtained.

Referring to the accompanying drawings forming part of this specification, Figure 1 is a sectional end elevation of a horizontal, four-cycle, double-acting internal combustion engine having a valve operating mechanism thereon constructed and arranged in accordance with my invention. Fig. 2 is a detail side elevation showing a modification in the construction of the valve operating mechanism also made in accordance with

this invention. Fig. 3 is a sectional elevation on a larger scale, the section being taken on the line III—III of Fig. 1, showing a detail of the valve operating mechanism and the means employed in adjusting the valve operating mechanism relative to the valves. Fig. 4 is a detail plan, on an enlarged scale, showing the construction of the bearing support and swivel bearing for the reach rods forming part of the valve operating mechanism.

In the drawings the numeral 2 designates a water-jacketed gas engine cylinder having an inlet port 3 and an exhaust outlet port 4, one of such ports being located at each end of the cylinders of double-acting engines like that shown. In a single acting engine only one inlet and one outlet port will be necessary. An inlet valve 5 and an exhaust outlet valve 6 removably secured in the inlet and outlet ports engage with the valve seats 7 and 8 also removably mounted in the ports 3 and 4. The cylinder 2 is also provided with openings or holes 9 and 10 in which the ignition or spark plugs for the engine are mounted, and the hole or opening 11 into the cylinder 2 provides for the attachment thereto of the cocks of an engine indicator, the opening 12 serving to make a suitable connection to the conduit of an air starting device.

The inlet valve seat 7 is connected by the spider 13 with the sleeve 14 through which the inlet valve stem 15 extends, the spider and sleeve being located within the mixing chamber 16 which is formed of a tubular shell 17 projecting downwardly into the casing 18. The shell 18^a in the casing 18 is provided with a series of openings 19 and 20 which are arranged to register respectively with similar openings 21 and 22 in the shell 17 in forming gas ports and air ports connecting the interior of the annular gas chamber 23 and air chamber 24 in the casing 18 with the central mixing chamber 16.

The tubular shell 17 is arranged to rotate or oscillate within the shell 18^a in the casing 18 to vary the size of the inlet ports formed by the openings 19, 21 and 20, 22, the closed outer end 25 of the shell 17 being provided with an arm 26 by which the shell 17 is connected to and operated by the engine governor (not shown) to vary the size of the air and gas ports to the mixing chamber 16 in regulating the speed of the engine.

The head 25 has an inward extension thereon which is bored to form a dash pot cylinder 27 and the inlet valve stem 15 which projects through the head 25 is provided with a piston 28, reciprocating within the cylinder 27 to cushion the valve 5 in its opening movement. Split piston rings are provided on the piston 28 to maintain a tight joint between the cylinder and piston and the vertical grooves 29 in the inner wall of the cylinder, at its upper end, provide means for the free admission of air thereinto on the lower side of the piston 28 when the inlet valve 5 is in its closed position, (the valve being lifted when moving into its closing position). When the piston 28, in the opening movement of the inlet valve, travels past the lower end of the grooves or slots 29 the air is confined within the cylinder 27 and, by further downward movement of the piston 28, is compressed therein, the size of the cylinder being proportioned so as to compress the air admitted therein to an extent sufficient to counterbalance the weight of the inlet valve 5 and its stem 15.

The exhaust outlet valve 6 has a hollow stem portion 30 which extends outwardly through the head 31 on the hollow water-cooled exhaust outlet chamber 32, this chamber having a side outlet 33 by which the exhaust pipe 34 is connected to the cylinder 2. The inner end of the chamber 32, which is located on the engine cylinder 2 to cover the exhaust outlet opening 4 therein, is preferably constructed to form an integral seat 8 for the exhaust outlet valve 6.

The valve operating mechanism will now be described and the operating mechanism for the inlet and the exhaust valves being of similar construction, the same reference numerals will be used for like parts thereof.

The outer end of the inlet valve stem 15 and also the outer end of the exhaust valve stem 30 is pivoted by a pin 36 to a swinging lever or arm 37 and one end of each arm 37 is pivotally connected by a pin 38 to one end of short links 39, 39 located on each side of each of the arms 37. The other end of the links 39 are pivoted by a pin 40 to and between the ears or lugs 41 on movable bases or supports 42, these bases being adjustably mounted on the outer end of the valve casting 18, and on the exhaust chamber 32 for the exhaust outlet. The bases 42 are secured in position on the cylinder by cap bolts or studs 43 (see Fig. 3) and a wedge 44, between the base 42 and the cylinder is employed to adjust the base 42 as required in bringing the valves into seating position after regrinding or renewal of the valves or the valve seats. Nuts 45, 45 on the two bolts 46 which form part of the wedges 44 and which project through holes or slots in the lugs 47 of the filler blocks 48 located on the end of the casing 18 and the chamber

32 provide means for adjusting and securing the wedges 44 in adjusted position. Also formed integrally on the upper face of the base 42 are standards or posts 49, 49 having slots in the ends thereof for bearings 50 which are held in position therein by set screws 51. Liners or shim plates 52, 52 in the slots on each of opposite sides of the bearings 50, (see Fig. 2) provide a convenient means for adjusting the bearings 50 in the slots to compensate for the increase in the length of the valve stems caused by the heating effect of the highly heated gases in the engine cylinder 2.

Mounted in each set of bearings 50, 50 is a pivot pin 53 to which one end of a bent wiping arm 54 is secured. The outer end of the bent wiping arms 54 which engage with and serve to positively move the arms 37, 37 in actuating the valves in their opening movement, are pivoted by a pin 55 to one end of a reciprocating reach rod 56 which extends through and is supported by a swivel bearing 57 (see Fig. 4,) pivotally mounted on a bracket 58, secured on one side of the casing 18 and the chamber 32 for that purpose. The other end of the reach rods 56 are connected by the lengthwise adjustable eccentric rods 59 to the strap of the eccentric 60 on the lay shaft 61 of the engine. At an intermediate point in the length of the reach rod 56 one end of an arm 62 is pivotally connected and the opposite end of this arm is bifurcated and is provided with a pin 63 on which a series of three anti-friction rollers 64, 64, 64 are mounted. In the operating mechanism for the inlet valve the middle rollers 64, mounted in the slots in the bifurcated ends of the rods 62 are arranged to contact with the lowermost face 105 of the arms 37 and the outside rollers 64, 64 ride on the upper face of the slides 65, which extend between the lugs or ears 41, and 49, on the upper face of the bases 42. In the upper face of the slides 65, 65, at one end thereof, is a recess or depression 66 into which the outside rollers 64, 64 enter at one end of their travel and when the valves are in their open position. On the exhaust valve operating mechanism the middle one 115 of the rollers 64 engages the upper face of the arm 37, and the outside rollers 64 ride upon the lower face of the slides 65.

The arm 37 connected to the stem 30 of the exhaust valve 6 has an outward extension 37^a which projects beyond the valve stem and loosely engages with one end of the piston rod 67 for the piston 68 in the balancing cylinder 69. This cylinder which is located adjacent to the exhaust valve chamber is 125 connected at one end by the pipe 70 with the interior of the gas engine cylinder 2. The piston therefor has a very short stroke, or a stroke just sufficient to slightly open the exhaust valve 6. The head 71 on the cylinder 130

has an inwardly extending hub or projection 72 through which the piston rod 67 extends and the inner end of this projection 72 limits the outward movement of the piston in the cylinder 69. The piston 68 is caused to move through its backward stroke by means of the helical spring 73 engaging with the cylinder head and with one face of the piston.

10 Split rings are provided in the piston 68 to insure a tight joint and the cylinder head 71 is connected by a pipe 74 to the exhaust pipe 34 of the engine to lead into the exhaust pipe any gases escaping past the piston and prevent the accumulation of burned gases and the formation of pressure on the rear side of the piston 68. The diameter of the cylinder 69 is proportioned so that it will exert a pressure on the end 37^a of the 15 lever 37 connected to the exhaust valve 6 sufficient to counterbalance the upwardly lifting valve and the moving parts connected therewith in the operation of the engine, in this way very much lessening the work 20 done by the valve operating mechanism connected to the engine lay shaft.

In the modified construction shown in Fig. 2 instead of using the fixed slides 65 to engage the outer anti-friction rollers 64, 30 slides 65^a are pivoted by one end to the lugs or ears 41 on the bases 42 and the opposite end of the slides 65^a is engaged by a helical spring 75 which lifts the free end thereof into engagement with the anti-friction rollers 35 so as to hold these rollers in contact with the lower face of the levers or arms 37. The construction of the valve operating mechanism of Fig. 2 otherwise is the same as has before been described.

40 In the operation of my improved valve actuating mechanism the engine is started preferably by means of compressed air supplied to the cylinder 2 through the inlet 12 which is connected to a source of air under 45 pressure. When in this or other desired manner the engine is started the lay shaft 61 is caused to rotate and the eccentric 60, through the connections to the bent wiping arms 54, opens one and closes the other of 50 the valves 5 and 6, the inlet and exhaust valves being alternately moved into open position, the eccentric 60, through the arms 62, positively moving the valves in their closing movement. On the return or closing 55 movement of the valves, the rollers 64, on the end of the arms 62 which roll along the faces of the slides 65 on the base 42, by engagement with the inner face of the arm 37 causes a positive movement of the valves 60 into closing position. Prior to starting the engine, the wedges 44 are adjusted to bring the valves 5 and 6 into close engagement with the valve seats 7 and 8, and after the engine has operated for sufficient time to be 65 come thoroughly heated any adjustment

found necessary, owing to increase in the length of the valve stems 15 or 30 in becoming heated, is made by shifting the liners 52 from one side to the other of the bearings 50 located in the slots in one end of the lugs 70 or ears 49 on the base 42 and in this way lost motion in the valve operating mechanism is avoided and overcome.

The advantages of my invention will be apparent to those skilled in the art. By the 75 novel arrangement of levers and arms connecting the valves with the eccentric, the length of the levers is greatly reduced, the desired quick opening and closing movement of the valves is obtained and the valves are held in closed position for the desired length of time during each stroke of the engine piston. The weight of the valves 5 and 6 and the resistance to the opening movement of the exhaust valve 6, caused by the pressure 80 in the cylinder 2 is counterbalanced by means of the dash pot cylinders operatively connected to the stems of these valves. The wiping arm 54 is arranged to move the levers 37 without hammering or knocking and by means of the adjusting mechanism used, lost motion in the valve operating mechanism is prevented and overcome. With the mechanism for operating the valves as constructed in accordance with this invention 85 the valves are positively moved through the opening and closing movements thereof and the valves are held positively in their closed position, (in which position the valves remain during the major portion of the stroke 90 of the engine piston).

I claim:—

1. In an explosive engine, a valve operating mechanism comprising a swinging arm to which the valve is pivoted, a wiping arm 105 engaging the swinging arm to positively move the valve into open position, a pivoted arm having rollers engaging the swinging arm to positively move the valve into closed position, means for actuating said arms, and means on which the wiping arm and the rollers of said pivoted arm are mounted, said means being movable on the engine to adjust the arms and valve relative to the seat therefor.

2. In an explosive engine, a valve operating mechanism comprising an arm support adjustably mounted on said engine, a swinging arm pivoted to the support and to a valve on the engine, a wiping arm pivoted to the support and arranged to engage the swinging arm to positively move the valve in one direction, a pivoted arm having means engaging the support and the swinging arm to move the valve in the opposite direction, means for adjusting the support on the engine, and means connected to the wiping arm and the pivoted arm for actuating said arms in opening and closing said valve.

3. In an explosive engine, a valve operating mechanism comprising swinging arms to which the engine valves are pivoted, wiping arms for moving the swinging arms in opening the valves, pivoted arms for moving the swinging arms to close said valves, means for actuating said arms to positively move the valves in opening and closing, and means secured to the engine on which said arms are mounted, said means being movable on the engine to adjust the arms and valves relative to the seats for said valves.
4. In an explosive engine, a valve operating mechanism comprising a swinging arm to which the valve is pivoted, a wiping arm engaging the swinging arm to positively move the valve into open position, a pivoted arm having rollers engaging the swinging arm to positively move the valve into closed position, means for actuating said arms, a support on which said arms are mounted and means for adjusting the wiping arm relative to the support and swinging arm.
5. In an explosive engine a puppet valve to close the exhaust outlet port and mechanism for positively actuating said valve in opening and closing, said mechanism having means connected with the interior of the engine cylinder whereby the valve is balanced in opening.
6. In an explosive engine having an inlet and an exhaust outlet port, and valves to close said ports, a valve operating mechanism comprising means to positively move said valves in opening and closing, and dashpot cylinders operatively connected thereto whereby the valves are balanced and cushioned in moving out of seated position.
7. In an explosive engine having an inlet port and a valve to close said port, a valve operating mechanism comprising means to positively move said valve in opening and closing, a piston on the rod of said valve and a dashpot cylinder operatively connected with the piston whereby the valve is cushioned in moving out of seated position.
8. In an explosive engine having an exhaust outlet port and a valve to close said port, a valve operating mechanism comprising means to positively move said valve in opening and closing, and a fluid pressure cylinder operatively engaging therewith whereby the valve is balanced in the opening movement thereof.

In testimony whereof, I have hereunto set my hand.

THOMAS W. KEEN.
